UNITED STATES PATENT OFFICE

171,868

ELECTRIC SOUND RECORDING AND REPRODUCING MACHINE

Edward Shipton, Northwood Hills, England

Application August 17, 1953, Serial No. 26,478

Claims priority, application Great Britain
February 27, 1953

Term of patent 14 years

(Cl. D26—14)

To all whom it may concern:

Be it known that I, Edward Shipton, a British subject, residing at Northwood Hills, Middlesex, England, have invented a new, original, and ornamental Design for an Electric Sound Recording and Reproducing Machine, of which the following is a specification, reference being had to the accompanying drawing, forming part thereof:

Fig. 1 is a front perspective view from above; and

Fig. 2 is a rear perspective view of an electric

sound recording and reproducing machine, showing my new design.

I claim:

The ornamental design for an electric sound recording and reproducing machine, as shown.

EDWARD SHIPTON.
